UNITED STATES PATENT OFFICE.

ERNST WOLFF, OF PFORZHEIM, GERMANY.

EXPLOSION-ENGINE.

1,142,073.

Specification of Letters Patent.

Patented June 8, 1915.

Application filed July 21, 1914. Serial No. 862,222.

To all whom it may concern:

Be it known that I, ERNST WOLFF, a subject of the German Emperor, and resident of Pforzheim, Germany, have invented certain new and useful Improvements in Explosion-Engines, of which the following is a specification.

This invention relates to improvements in explosion-engines, for instance for motor-cars, and more particularly to an improved combined exhaust silencer, purifier and deodorizer for the same. Besides performing its intended function in a reliable way, the improved device has the advantage that, by the use of the same, the strong resistance exerted on the piston by the products of combustion in the explosion-chamber during the return stroke of the piston as soon as the engine is excessively strained, is considerably decreased.

In the accompanying drawing: Figure 1 is a plan of the improved device, with a view into the interior of the water container, Fig. 2 is a view of said container from that side to which the exhaust gases are supplied, Fig. 3 is a vertical cross-section through the water container, at right angles to the longitudinal axis of the same, Fig. 4 is a cross-section through the condenser ball, Fig. 5 is a vertical section through the whole device, in the direction of its longitudinal axis.

On the two longitudinal beams *a*, *b* of the vehicle frame the transverse stays *c*, *d* are fixed, from which the container *e*, *f* is suspended. The latter is divided into two parts by a vertical partition-wall. The gases arriving from the engine enter the sheet-iron box *u* through the pipe *f*, said box being centrally built in the cylinder *s*. Box and cylinder are screwed with flanged rings to the outside of the container *e* (Fig. 5). The inner end of the box *u* has on its circumference a plurality of elongated slots, which are also provided in the front end of the cylinder *s* on the opposite side, so that the gases are compelled to flow first to the left, then between *u* and *s* to the right, and finally through the latter slots again to the left. Thereupon, they enter the container *e* through the pipe *o*, which container is filled with water or the like somewhat above half of its height. On the bottom of said container, an outlet, and on its side an overflow device is provided. On this container *e* a dome-like head *r* is mounted, which is closed by a cover *g*. Below the lat-

ter the pipe *o* leads into an oval, grate-like mouth *p*, which is directed toward the water level (Figs. 1, 3 and 5), the interstices of which form a sufficient outlet cross-section for the gases and, by dividing the latter into separate currents, considerably soften the shocklike advance of the same. The shape of said interstices makes a stopping of the same by impurities practically impossible, because the latter are very fine and do not find sufficient hold on the edges of the interstices. The gases meet the water level in practically vertical direction, expand then to all sides and deliver their solid ingredients thereto; particularly the volatile oil particles settle the more, the warmer the water becomes during its use. The lead-off pipe *h* terminates in the steam-dome *r* with upwardly directed opening *q*, so that any rigid ingredients, as well as the water itself, cannot pass to the pipe orifice at violent vibrations or inclined position. The pipe *h* leads now the waste gases through two knees into the sheet-iron ball *i*, containing a hemispherical receiver *w* (Fig. 4), which on its inner side is closed by the flat ball-piece *y*, so that the gases are compelled to take their way through the slots in the hemisphere *w* into the interior of the funnel *x* facing the latter, and finally through the pipe *h* to the outlet opening *z*.

During their passage through the ball *i*, the gases are considerably cooled, particularly owing to the air draft acting on said ball with vehemency. Thereby, on the deepest point of the ball condensed water is collected, which is led back through the pipe *m* to the exhaust pipe *o*. The pipe *m* is sloping from the ball *i* to the container *e* and is bent at its end in the lead-off pipe *o* in the direction of the same, so that it forms the nozzle *n*. Thereby, the condensed water collected in the ball *i* together with any other sediments and impurities runs automatically back to the pipe *o*. Besides, by this arrangement, a further effect is created, which makes itself particularly conspicuous with motor-cars. With the latter, the engine when climbing up hills was considerably strained, so that more fuel must be supplied thereto, the quantity of which could however not be determined corresponding to the higher capacity of the engine, while further any surplus of fuel could not be completely consumed, because the explosion-chamber was incapable to receive the quantity of air

required therefor. Thereby, more products of combustion were produced and, further, the already high pressure of the waste gases was still increased by the gasification of the 5 excess of fuel, so that the waste gases could not quickly enough escape from the explosion-chamber, but had to be pressed out by the returning piston with a high expenditure of power. This counter-pressure requires 10 ways a considerable loss of power, as the capacity produced by the explosion is thereby partly neutralized, while a large quantity of unburnt fuel was consumed. The gases ejected form, as known to any motorist, 15 large clouds behind the motor-car and are of great nuisance for the passengers. By leading, however, the pipe *m* into the lead-off pipe *o*, by the exhaust gases not only the condensed ingredients are sucked out of the 20 ball *i* but also the pressure of the gases therein is considerably reduced and that the more the higher becomes the pressure of the waste gases by an excessive strain of the engine. In this connection, it is of particular advantage 25 that the sucked-off gases, by their being cooled, assume an essentially smaller volume than previously when escaping from the pipe *o*, which is particularly favorable for the suction effect. This arrangement controls therefore automatically the sucking-off 30 of the exhaust gases and the pressure of the same and effects, as proved by repeated experiments with motor-cars, a considerable saving of power; particularly, when climbing 35 up hills, the engine works in an essentially easier way.

By the exhaust gases having to travel before entering the container, one, and, after passage through the same, a multiple indirect way, the same are cooled and suspended liquid or solid ingredients are eliminated therefrom, while at the same time the shock-like advance of the gases is gradually converted into a uniform, continuous movement. 40 45 By the gases meeting the water level in the

container *e*, all non-gasified particles therein are kept back by the water, while avoiding the drawbacks hitherto connected with such devices. The latter consist of the fact that, when leading the gases into the water, the 50 latter did not only offer a considerable resistance but it was also, with a high gas pressure, caused to partly flow along with the latter, so that it was finally so much reduced that the pipe did not more completely 55 dive into the water, whereby the gases could escape in non-purified condition. The passage of the gases through purifying matters spread on strainers had the drawback that the latter, besides offering a considerable resistance, were soon stopped, so that the device could not more operate. An emptying and renewal of the purifying matter was, however, practically impossible if this happened on the way. All these drawbacks are 60 65 completely overcome by the improved arrangement, by which also the escaping exhaust gases are completely silenced.

What I claim, is:

In a combined exhaust silencer, purifier 70 and deodorizer for explosion-engines, the combination of a water container, a plurality of receptacles through which the exhaust gases pass, an exhaust pipe with grate-like mouth to lead the gases into said water container vertically to the water level after their passage through said receptacles, a hollow ball having funnels with baffle devices to receive said gases after their passage through the water container, a pipe to 75 communicate between the lower end of said ball and said exhaust pipe and forming a nozzle in the latter, and a pipe to lead the gases from the ball into the atmosphere, substantially as and for the purpose set forth. 80 85

ERNST WOLFF.
